[57] CLAIM

The ornamental design for a universal support bracket for hanging and suspending articles, as shown and described.

DESCRIPTION

FIG. 1 is a perspective view of a first embodiment of a universal support bracket for hanging and suspending articles showing my new design from the front and top;

FIG. 2 is a side elevation thereof;

FIG. 3 is a perspective view thereof shown from the rear and bottom;

FIG. 4 is a perspective view of a second embodiment of the universal support bracket for hanging and suspending articles showing my new design from the front and top; and,

FIG. 5 is a perspective view thereof shown from the rear and bottom.
